(57) **CLAIM**

The ornamental design for a bag, as shown and described.

DESCRIPTION

FIG. 1 shows a front elevation view of a bag;
FIG. 2 shows a rear elevation view of the bag of FIG. 1;
FIG. 3 shows a left side elevation view of the bag of FIG. 1;
FIG. 4 shows a top view of the bag of FIG. 1; and,
FIG. 5 shows a bottom view of the bag of FIG. 1.
The right side elevation view is a mirror image of the left side
elevation view.
